CLAIM

The ornamental design for an in-vehicle camera device, as shown and described.

DESCRIPTION

FIG. 1 is a front elevational view of an in-vehicle camera device showing our new design;
 FIG. 2 is a rear elevational view thereof;
 FIG. 3 is a left side view thereof;
 FIG. 4 is a right side view thereof;
 FIG. 5 is a top plan view thereof;
 FIG. 6 is a bottom plan view thereof; and,
 FIG. 7 is a perspective view thereof.

The broken lines depict portions of the in-vehicle camera device in which the design is embodied that form no part of the claimed design.
